UNITED STATES PATENT OFFICE.

GEORGE F. DANA, OF CINCINNATI, OHIO.

MOP-WRINGER.

1,071,144.

Specification of Letters Patent.

Patented Aug. 26, 1913.

Application filed January 20, 1913. Serial No. 743,154.

To all whom it may concern:

Be it known that I, GEORGE F. DANA, a citizen of the United States, residing at Cincinnati, in the county of Hamilton and State of Ohio, have invented certain new and useful Improvements in Mop-Wringers, of which the following is a specification.

My invention relates to a combined mop-wringer and bucket, wherein the mop is confined between rollers normally disposed apart from each other to permit free insertion of the mop into the bucket, one of said rollers being capable of being moved toward the other under pressure to press the mop 15 between them in withdrawing the same.

To prevent the mop from spreading beyond the ends of the rollers, guides are provided adjacent their ends.

This invention is primarily directed to 20 the mounting of the rollers and the construction and operation of the guards.

An object of my invention is to provide a 25 mop-wringer with a pair of pivotally mounted guards, adapted to support and journal a pair of horizontally disposed parallel rollers at one end with the opposite end of each engaged with the axle of a movable roller journaled upon an operating lever. The axle of the movable roller projects 30 through a longitudinal slot in each of the guards to accommodate for its arc of movement toward the stationary rollers and thereby enable the guards to be mounted between the respective ends of the movable 35 roller and limbs of the operating lever to offer rigidity to the guards during a mop-wranging operation. The pivotal mounting of the guards enables the axle of the movable roller to be journaled in permanently 40 located bearings in the operating lever.

Further objects of my invention relate to 45 oscillating guards disposed adjacently to the wringer rollers with the free ends engaged with the axle of the movable roller of the series, the axles projected through a longitudinal slot in each of the guards. Such guards enable the movable roller to be 50 engaged therewith and be mounted in permanent bearings in the operating lever therefor and offer no resistance to the operation of the parts.

The features of my invention are also 55 directed to the specific form of construction of bucket mop-wringer illustrated in the drawings and which is more fully set forth

in the description thereof herein, forming a part of this specification, in which:—

Figure 1 is a mutilated side elevation of my improved bucket mop-wringer, showing the upper portion of the bucket and wringer elements in section. Fig. 2 is a front elevation thereof, with the upper portion of the bucket cut away to more clearly illustrate the wringer elements depending within the bucket. Fig. 3 is a detailed sectional view of a modified form of wringer, in which only two rollers are comprised instead of three, as illustrated in Fig. 1.

1 represents the bucket, having the bracket 2 secured at the upper portion of its inner 70 periphery. The bracket is preferably formed of a strip of metal bent to substantially U-form, with the major portion thereof conforming to the curvature of the bucket, and with the limbed extremities 3, providing bearings for the pivot rod 4. The rod 4, in one instance, forms the axis for the guards 5 when the wringer is of the three roller type, and the axle of the roller 4^a in a two-roller type. Two guards 5 are provided, one mounted adjacent each limb 3 of the bracket and preferably adjacent the interior surface thereof, with the roller or rollers intermediate of the guards. In the three roller type of wringer, each guard 75 comprises a metal plate having the oppositely disposed right angled ear extensions 6 and 7 serving as bearings for journaling the stationary rollers 8 and 9 arranged in superposed parallel planes. The ear extensions 6 and 7 are omitted in the two roller type as shown in Fig. 3, the roller 4^a being mounted on the rod 4 which forms the axis for the guards. The guards are also 80 each provided with a longitudinal slot 10 in 90 a plane with the pivot rod 4, through which the axle 11 of the movable roller 12 projects, providing clearance for the roller movement toward and from its companion rollers 8 and 9.

100 The movable roller 12 is mounted between the pair of limbs of an operating lever of peculiar construction, which lever is pivotally mounted upon the exterior of the bucket and operated by the foot of the operator. 105 The lever comprises a bowed or semi-circular portion 13 extending around one-half of the exterior of the bucket and the oppositely disposed vertical limbs 14, 15, secured respectively to the ends of the bowed 110

portion 13 and substantially at right angles thereto, with the ends of said limbs bowed inwardly and dependingly into the bucket. Between these depending portions of the limbs of the operating lever, the roller 12 is mounted with its axle 11 projected through an orifice in each of said limbs.

17 represents cross struts, each fixed to a vertical limb and bowed portion 13 of the lever for reinforcement.

18 represents oppositely disposed pivot plates secured to the exterior of the bucket, each having a projecting boss terminating in a pintle 19, adapted to engage through an orifice, in each of the limbs 14, 15, respectively, of the operating lever. Each plate has a spring 20 engaged therewith and with a limb of the lever, its coil encircling the projecting boss of the plate, for urging the lever and its roller to normal position. The use of two springs, one upon each side of the lever equalizes the force, insuring freer operation of the lever.

21 represents a tread radiating intermediate from the bowed portion 13 of the operating lever, adapted to be engaged by the foot of the operator to depress said lever. 22 represents a stationary tread secured to the bucket, whereby the bucket can be held in position on the floor to prevent it from tilting during a wringing operation.

It will be noticed that the forward ends of the guards engage with the axle of the movable roller 12, through the longitudinal slots, and are disposed between the ends of the roller and lever limbs respectively, while the rearward ends are adjacent the inner faces of the bracket ears. This provides a secure connection for the guards, maintains the same adjacent the ends of the rollers during a mop-pressing or wringing operation, serving to prevent the strands of the mop from becoming entangled with the roller axles and materially resists outward flexing torsion of the guards.

The pivotal mounting of the guards offers free movement of the operating lever through the longitudinal slots, making it possible to provide permanent bearings in the operating lever for the axle of the movable roller, connecting the parts against displacement.

In practice the mop is dropped into the bucket, between the guards and rollers in open position, the bell crank lever is operated, the single roller moves toward the fixed bearing rollers, the free ends of the guards rocking upwardly to permit of this movement and to guide the roller toward the rollers 8 and 9 in axial plane with the rod 4, at the same time this rocking of the guards relative to the bearing bracket, tilts the pair of rollers at an angle to the vertical plane, causing the rollers to maintain their relative planes when the mop is withdrawn between them. This effectively squeezes without injuring the mop and is a simple, easy operation. There are no bindings because the only guide slots are in the guards which rock freely to accommodate for the arc of travel of the third roller as it is carried by the bell crank.

Having described my invention, I claim:

A mop-wringer comprising a bearing bracket secured to the inner bucket periphery upon one side thereof, a pair of roller-supporting slotted guide arms, pivotally secured to said bracket at their inner ends, their outer free ends extending across the mouth of the bucket, a pair of rollers having bearings in the hinged portion of said arms above and below said guide slots, a yoke-form bell crank lever fulcrumed exteriorly on the lower portion of the bucket, one end being formed with a foot-piece at one side of the bucket, the other end extending over the top of the bucket and being bent downwardly into the mouth of the bucket on opposite sides thereof, and a third roller having its axle extended through said bell crank lever upper ends, whereby the roller slides in said slots to and from said pair of rollers, the free ends of said guards rocking to angularly adjust the fixed rollers and guide the third roller as it moves to and from the wringing position.

In testimony whereof, I have hereunto set my hand.

GEORGE F. DANA.
